(57) **CLAIM**

The ornamental design for a brassiere-wing back closure, as shown and described.

DESCRIPTION

FIG. 1 is a front view of a brassiere wing back closure showing my new design;

FIG. 2 is a side view of first closure;

FIG. 3 is a small scale front view of the female part thereof of conventional thickness shown separately for purposes of illustration;

FIG. 4 is a small scale front view of the male part thereof of conventional thickness shown separately for purposes of illustration;

FIG. 5 is a small-scale back view of the female part of the invention;

FIG. 6 is a small-scale back view of the male part of the invention;

FIG. 7 is a front view of a brassiere wing back closure of a second embodiment showing my new design;

FIG. 8 is a side view of the second closure;

FIG. 9 is a small scale front view of the female part thereof of conventional thickness shown separately for purposes of illustration;

FIG. 10 is a small scale front view of the male part thereof of conventional thickness shown separately for purposes of illustration;

FIG. 11 is a small-scale back view of the female part of the second closure according to the invention;

FIG. 12 is a small-scale back view of the male part of the second closure according to the invention;

FIG. 13 is a front view of a brassiere wing back closure of a third embodiment showing my new design;

FIG. 14 is a side view of the third closure;

FIG. 15 is a small scale front view of the female part thereof of conventional thickness shown separately for purposes of illustration;

FIG. 16 is a small scale front view of the male part thereof of conventional thickness shown separately for purposes of illustration;

FIG. 17 is a small-scale back view of the female part of the third closure according to the invention; and,

FIG. 18 is a small-scale back view of the male part of the third closure according to the invention.

The broken lines form no part of the claimed design.
